DESIGN FOR A FOLDING DOOR HANDLE

Lee Segar, Troy, Pa.

Application April 23, 1935, Serial No. 56,525

Term of patent 14 years

To all whom it may concern:

Be it known that I, Lee Segar, a citizen of the United States of America, residing at Troy, in the county of Bradford and State of Pennsylvania, have invented a new, original, and ornamental Design for a Folding Door Handle, of which the following is a specification, reference being had to the accompanying drawing, forming a part thereof.

Figure 1 is a perspective view of a folding door handle, showing my new design.

Figure 2 is a side elevation.

Figure 3 is a rear elevation.

Figure 4 is a sectional view taken on the line 4—4 of Figure 2.

I claim:

The ornamental design for a folding door handle, as shown.

LEE SEGAR.
